UNITED STATES PATENT OFFICE.

CHARLES EDWIN SNELL, OF CHATHAM, CANADA.

DESIGN FOR REED-ORGAN PIPES.

Specification forming part of Design No. 5,207, dated August 15, 1871.

To all whom it may concern:

Be it known that I, CHARLES EDWIN SNELL, of Chatham, in the county of Kent and Dominion of Canada, have invented a new and useful Improvement in Design for Resonant Pipes for Reed-Organs and like instruments; and I do declare that the following is a true and accurate description thereof, reference being had to the accompanying photographic illustration and being a part of this specification, in which my design is clearly shown.

The nature of the invention relates to the form and shape of compound resonant pipes or tubes to be employed in reed-instruments, such as melodeons and other instruments of a similar construction, by means of which the power and tone of the instrument are materially increased and made to assimilate that of a pipe-organ.

The invention consists in the form and shape

of a series of tubes laid horizontally, and their rear ends terminating in tubes of a similar construction standing at a right angle with the horizontal tubes. The fronts of the latter engage with and receive the tone emitted from the reeds of the instrument, which is then increased in volume, and converted from a reed to a pipe-tone in its passage through the tubes, and is emitted therefrom through suitable openings near the top of the vertical or angling extensions.

What I claim as my invention, and desire to secure by Letters Patent, is—

The design for resonant pipes or tubes, as described and shown.

CHARLES E. SNELL.
